UNITED STATES PATENT OFFICE.

EDWARD F. CALDWELL, OF NEW YORK, N. Y., ASSIGNOR TO THE PHOENIX
GLASS COMPANY, OF PITTSBURG, PENNSYLVANIA.

DESIGN FOR A GLOBE OR SHADE.

SPECIFICATION forming part of Design No. 26,645, dated February 16, 1897.

Application filed January 13, 1897. Serial No. 619,128. Term of patent 7 years.

To all whom it may concern:

Be it known that I, EDWARD F. CALDWELL, a citizen of the United States, residing at New York, in the county of New York and State of New York, have invented a certain new and useful Design for a Globe or Shade; and I do hereby declare the following to be a full, clear, and exact description of the invention, such as will enable others skilled in the art to which it appertains to make and use the same.

My invention has relation to designs for gas, electric, and other globes or shades used in illuminating; and it consists in the shape and configuration herein described and illustrated.

In the accompanying drawings, Figure 1 is a plan view, and Figs. 2 and 3 are side views, of a globe embodying the design.

The body of the globe is bell-shaped, with

the lower half nearly cylindrical and curved abruptly inward at its base to meet the neck *b*. The upper edge or mouth is scalloped and the edges of the scallops beveled externally, so as to present the ornamental wavy-edge line *d*, which is cut and polished.

The surface of the globe may be frosted and ornamented with appropriate harmonious etching.

What I claim as new is—

The design for a globe or shade as herein described and illustrated.

In testimony whereof I have affixed my signature in presence of two witnesses.

EDWD. F. CALDWELL.
